UNITED STATES PATENT OFFICE.

EDWIN H. WEDEKIND, OF SAN FRANCISCO, CALIFORNIA; H. C. HAAS ADMINISTRATOR
OF SAID EDWIN H. WEDEKIND, DECEASED.

SUBLIMING APPARATUS.

Application filed June 8, 1921. Serial No. 475,431.

My invention relates to an apparatus for subliming certain metals and the collection of the products of sublimation. Among the objects of the invention is the provision 5 of a process of and apparatus for accomplishing the results recited which is characterized by a high degree of efficiency and economy and in which the collection of the products of sublimation is accomplished by 10 mechanical means working automatically.

My invention possesses other objects which together with the foregoing will be set forth in the following description of the preferred process and the preferred embodiment 15 of means for practicing the same, which is illustrated in the drawings accompanying and forming part of the specification. It is to be understood that I do not limit myself to the showing made by the description and drawings as I may adopt 20 variations of my preferred form within the scope of my invention as set forth in the claims.

Referring to the drawings:—

Fig. 1 is a plan view of a subliming apparatus in which my process may be carried on. A portion is broken away to better disclose the structure. Fig. 2 is an elevation of the subliming apparatus, portions being 25 broken out to reduce the size of the figure and to show the structure of the apparatus. Fig. 3 is a vertical sectional view thru a portion of the apparatus. The plane of section is indicated by the line 3—3 of Fig. 1. Fig. 4 is a vertical sectional view transversely across one of the units of the apparatus. The plane of section is indicated by the line 4—4 of Fig. 1.

My process is applicable to the subliming 40 and collecting of any metal which is volatile at higher temperatures and which upon cooling returns again to the solid state as a metal or as a stable salt, such for instance, as arsenic, antimony, lead or zinc to which 45 my process is particularly applicable.

Hitherto the subliming of these metals has involved treating their ores in furnaces or retorts. In some of these oxygen is admitted to form oxide of the metals; in 50 others, chlorine and sulphur may be admitted to form the corresponding combination and in the case of retorts the metals are condensed without forming salts or other combinations. Up to the present time sublimation of the metals referred to is effected al- 55

most entirely in brick or concrete chambers. In some cases the chambers are built of sheet metal, such as copper and sheet steel, and in others the cooling takes place in cast iron pipes. In all however the sublimed materials are collected by scraping from the walls by hand and removing the same from the chambers. It is obvious that under such conditions the work of cleaning the chambers is both difficult and dangerous, and it 60 is necessary to provide the workers with safety devices for the protection of eyes and respiratory organs.

In the present specification I shall explain my process with especial reference to arsenic, 70 antimony, zinc, and lead, all of which combine with oxygen obtained from atmospheric air to form oxide but for the purpose of simplicity I shall treat particularly of the recovery of arsenic trioxide in sublimed form from arsenic bearing ores. In accordance with my invention I conduct the furnace gases thru a series of conduits or chambers regulating the temperature of the forming combinations of sublimation by permitting a gas under pressure to expand therein. Prior to the entrance of the gases into the subliming chamber and under the high temperatures to which they are subjected the combination takes place and the products 80 crystallize, but on a sudden reduction of temperature in the subliming chambers crystallization ceases, the product being then amorphous, and deposits on the walls of the subliming chambers. Mechanical means are provided for loosening this deposited material and collecting it in the bottom of the chambers from which it is removed by a 85 screw conveyor acting continuously.

The apparatus with which my process may be carried out comprises preferably a series of chambers 2 formed in the housing 3 by means of transverse partition walls 4 which extend outwardly in radiating flanges 5. The partition walls are provided with apertures 6, the apertures being arranged on opposite sides of the chamber alternately so that a baffled effect is produced upon the flow of gases thru the chambers. The housings 3 are arranged parallel to each other and connected in series by conduits 7 which rise from the housing and join at sharp angles, being as nearly vertical as possible so that the sublimed product does not tend 100 to collect in the connecting pipes. One end 105

of the first housing is connected by conduit 8 with a dust collector 9, of known form, which in turn is connected to the furnace 11 which may be of any desired type. The 5 first housing is the smallest of the group or battery, the others increasing progressively in size until finally the treated gases enter the largest housing and are discharged thru conduit 12 at the end thereof into the air or into other apparatus for further treatment.

The shape of each housing is in general, cylindrical, but the lower portion thereof on each side extends tangentially toward a trough 13 which extends longitudinally the 10 whole length of the housing.

Journaled in suitable bearings in the housing is a hollow shaft 16 one end of which is connected by a suitable coupling with a pipe 17 which extends across the end 20 of the battery of housings and which supplies air under pressure to each of the shafts 16. Fixed on the shaft in each chamber 2 is a frame 18 extending on opposite sides of the shaft in a balanced structure nearly to the 25 wall of the chamber. On each side of the frame is bolted a scraper 19 so that with the rotation of the shaft the walls of the chamber are swept by the scraper. In the drawings I have shown a scraper comprising 30 a solid blade but if preferred a wire brush may be substituted for the blade. A series of small pipes are also arranged on the frame, a pipe lying on each edge of the frame parallel to the wall of the chamber 35 and quite close thereto. The pipes are connected into the hollow shafts 16 and receive air therefrom, the air escaping in jets from apertures 20 formed in the pipe. The apertures in the outer pipe are arranged so that 40 the jets of air strike the walls of the chamber and assist the scraper blades in keeping the walls clear. The troughs 13 are provided at intervals with discharge spouts 21 and in each trough is disposed a spiral conveyor 22 driven by a chain 23 extending across one end of the battery of housings and receiving motion from a sprocket 24 driven by any suitable prime mover. A second sprocket 26 on each conveyor shaft is 45 connected by chain 27 with a relatively large sprocket 28 fixed on the end of each of the hollow shafts 16. The sprocket 24 is driven at low speed and during the operation of the apparatus the screw conveyors 50 and the shaft 16 are in continuous slow movement.

For purposes of illustration it will be assumed that the apparatus is being used for subliming the arsenic salt As_2O_3 . The volatilized gases enter from the furnace thru the conduit 8 into the first housing and the first chamber thereof passing thru the apertured baffle partition 4 into the second chamber and so on thru the series of chambers. 65 As the arsenic laden gases pass thru the

chambers they are stirred by the revolving frame and thoroughly mixed with the jets of expanding air issuing from the rotating pipes. The cooling effect of the expanding air effects the condensation of the sublimed 70 product of salt which is deposited on the walls of the chamber and almost immediately swept therefrom toward the trough at the bottom of the chamber. The conveyor at the bottom of the housing constantly removes the accumulated product, and because of the arrangement of the discharge spouts the product of various portions of the apparatus may be segregated. This is important since the cooler parts of the apparatus 75 will produce a higher grade product than that sublimed in the hotter portion. Thus the collection of the sublimed product is carried on automatically at a rate commensurate with the deposit of the product in the 80 subliming chambers.

I claim:

1. A subliming apparatus, comprising a chamber, means for injecting into said chamber jets of air under pressure, and means for 90 scraping the wall of said chamber to free the sublimed product therefrom.

2. A subliming apparatus, comprising a chamber, means for injecting into said chamber jets of air under pressure, means for 95 scraping the wall of said chamber to free the sublimed product therefrom, and means for removing from the bottom of the chamber the accumulated product.

3. A subliming apparatus, comprising a 100 chamber, means for injecting into said chamber jets of air under pressure, means for scraping the wall of said chamber to free the sublimed product therefrom, and a screw 105 conveyor disposed in the bottom of said chamber.

4. A subliming apparatus comprising a housing of generally cylindrical form and provided with a trough on the lower side thereof, means for injecting into said housing jets of air under pressure, means rotatably mounted in said housing for scraping the sublimed product from the wall thereof into the trough, and a conveyor in said trough for removing the product therefrom. 110

5. A subliming apparatus comprising a 115 housing of generally cylindrical form and provided with a trough on the lower side thereof, a frame rotatably mounted in said housing, means on said frame for sweeping the wall of the housing, perforated pipes on said frame, means for supplying said pipes with air under pressure and a conveyor in said trough.

6. A subliming apparatus comprising a 120 chamber, a frame rotatably mounted in said chamber, means on said frame for sweeping the wall of the chamber, perforated pipes on said frame, means for supplying said pipes with air under pressure, and a 125

conveyor for removing from the chamber the sublimed product.

7. A subliming apparatus comprising a plurality of chambers connected in series, means for introducing volatile products from the furnace at one end of the series of chambers, means for baffling the flow of gases thru said series of chambers, means for injecting into each chamber jets of air under pressure, rotary means for sweeping the walls of each chamber, and a conveyor in each chamber for removing the sublimed product therefrom.

8. A subliming apparatus comprising a plurality of connected chambers, said chambers merging at the bottom into a trough in which the sublimed material from each chamber tends to collect, a conveyor in said trough for removing the material therefrom, and spaced discharge spouts in said trough to permit the products of the several chambers to be separately discharged.

In testimony whereof, I have hereunto set my hand:

EDWIN H. WEDEKIND.
